UNITED STATES PATENT OFFICE.

PETER COOPER HEWITT, OF RINGWOOD MANOR, NEW JERSEY.

GLIDING CRAFT.

1,164,346.

Specification of Letters Patent. Patented Dec. 14, 1915.

Application filed August 26, 1908. Serial No. 450,351.

To all whom it may concern:

Be it known that I, PETER COOPER HEWITT, a citizen of the United States, and a resident of Ringwood Manor, in the county of 5 Passaic and State of New Jersey, have invented certain new and useful Improvements in Gliding Craft, of which the following is a specification.

This invention relates more particularly 10 to craft in which the support and balance depend partially or wholly upon dynamic reaction or displacement of the fluid medium.

It concerns more particularly aeroplanes 15 and the maintenance of their stability by means of gravity. Stability requires the maintenance within limits of certain relations between the distribution of weights, distribution of lifting efforts, and the direction 20 of pull of gravity, as well as between head resistance, propelling power, and the direction of movement. In the case of the aeroplane, the medium traversed is seldom in a state of rest, and being highly elastic, 25 the directions and velocities of its movements are non-uniform. Moreover, the medium is extremely light, and any craft capable of supporting a useful load, must be of very considerable surface area, and if 30 supported solely by dynamic reaction, must be driven at considerable speed. Hence, in practice, the device as a whole traverses regions of air having differently varying movements and lifting effects, and, by reason 35 of its necessarily large area, it frequently happens that different parts of the area are simultaneously traversing differently reacting regions. It results from this non-uniformity of the medium that mere symmetry 40 of distribution of areas and weights is insufficient to insure stability, and, in practice, it is necessary to compensate for the varying lifting efforts exerted on different portions of the lifting area, by varying the 45 lifting effort at certain points, so as to maintain stability, as, for instance, by increasing the area at one side or increasing the deflecting angle of part or all of the deflecting or supporting and lifting area with respect to 50 the weights and to the direction of pull of gravity.

In accordance with my invention, the tilting movement and the resulting shift of deflecting areas and weights with respect to 55 the direction of pull of gravity, is utilized to produce automatically a correlative shift

ing of lifting efforts, tending to oppose or correct tilt. The weights utilized are preferably weights which would be necessary in any event, such as the weight of the motor or load, and the correcting effort may be produced by arranging matters so that the dynamic lift or its effective leverage with respect to the center of weight and the direction of pull of gravity are one or both 60 increased on the down tilting side. In certain cases, the deflecting areas are arranged so that tilting causes the down tilting portion to deflect the air more directly downwardly, thereby increasing the vertical component 65 of the dynamic reaction on said portion. These correctional changes of leverage and vertical component of the reaction may be produced solely as the result of the tilting of the structure, the distribution of 70 deflecting areas, and of weights being structurally fixed relatively to each other, but variable with respect to the direction of pull of gravity, and in other cases, part of the weight of the craft, as the motor or 75 load, or both, is free to maintain a constant vertical direction with respect to gravity, after the manner of a pendulum, and when the deflecting area tilts, its relative movement with respect to the pendulum is utilized to correct the tilt. This may be accomplished through suitable mechanical connections causing increase of deflecting area or angle on the down tilting side, or decrease 80 on the uptilting side, or both. 85

In order to insure the various correcting effects above described, the craft is so designed that the center of resistance to forward movement is above the center of weight, and the center of propulsion is also above the center of weight and is preferably located so that its center is substantially the same as the center of resistance to forward movement. The location of the propellers is to a large extent determined 95 by the areas exerting the lift. While the average or center of resistance of the structure is located above the center of weight, certain areas are definitely located with reference to the degree of stability required, 100 the stability being dependent on the position of certain terminal areas of the deflecting surfaces with reference to their distance above the center of weight, both as to the height above such center and the distance 105 horizontally therefrom. A lifting effort applied at a point directly over the center of

weight will have no rotating effect which could serve either to cause tilting or to correct it, because the lift and the weight act in direct opposition to each other in the same vertical line. If, however, the lifting effort is exerted any where outside of such vertical line, the forces of lift and weight form a couple, the tilting effort of which is proportional to the product of the lift multiplied by the horizontal distance of the vertical line of lift from the vertical line of pull of gravity at the center of weight. Hence, by my invention the craft is constructed so that part of the deflecting area is located at a considerable distance horizontally from a vertical line through the center of weight and also a predetermined, desired distance above a horizontal plane passing through the center of weight. It results from this space relation that any tilt of the structure above the center of weight, will carry the lifting area to a point where its horizontal distance from the center of weight is greater or less according as the area is on the down 25 tilting or up tilting side. For a given change of tilt, the change of tilting leverage of any element of the lifting area used as an automatic correcting factor, is proportional to the product of the initial horizontal 30 distance of said element from the vertical line of pull of gravity at the center of weight, multiplied by the additional horizontal distance to which said element of the surface is carried by the tilting action. For 35 tilt through a given angle, said additional horizontal distance is proportional to the initial vertical distance of the surface above the plane of the center of weight. For all surfaces at the same height above said plane, 40 the additional horizontal distance through which they are moved by tilting through a given angle is the same, but the above described product representing the change of leverage is proportional to the initial distance of the portions of the surface from the vertical line through the center of gravity. Hence, other things being equal, the portions of the surface most remote from the center of gravity are most effective in 45 correcting tilt by change of distance. In most cases, the same thing is true with respect to correcting tilt by increasing the vertical component of the dynamic reaction, and accordingly, in certain cases, the tips or 50 lateral extremities of the deflecting area are enlarged fore and aft and the extreme forward and aft deflecting surfaces are enlarged laterally so that larger areas will be available in the locations where they are 55 most effective.

For relatively fixed symmetrical lifting areas symmetrically disposed on each wing at equal distances above the horizontal plane of the center of gravity, the increase of 60 leverage of the lift on the one side, will be

equal to the decrease on the other side, and any incipient tilting movement will cause the amount of each to vary automatically on the two wings in accordance with and in opposition to such tilting movement.

The above expedients for correcting tilt have been described more particularly with respect to lateral tilt, but, in accordance with my invention, the same relations and expedients are utilized to correct fore and aft tilt.

I prefer to distribute the operative surface of the wings or deflecting areas laterally across the line of flight to such extent as is necessary to get the required dynamic 80 lifting area without making the wings too wide fore and aft and certain parts of the area are located above the plane of the center of weight, the amount of such area and its distance from said plane being such as is necessary to secure the desired amount of 85 automatic change of lifting power (lift leverage) necessary to insure the correcting effect necessary for stability.

In certain cases I prefer to arrange the 90 deflecting areas at the top and bottom surfaces of a substantially straight, parallel sided, rectangular truss, in which case all of the deflecting areas on the upper side of the truss are vertically equidistant from the 95 horizontal plane passing through the center of gravity. In this case tilting movement serves to change the lift or vertical component of the dynamic reaction uniformly on both wings, but the effective leverage of the 100 lift becomes greater on the down tilting side and less on the up tilting side. In other cases, the planes may be upwardly bent or inclined from the center toward the tips, in which case those farthest from the center 105 of gravity will be highest above the horizontal plane passing through the center of gravity. In this case, both leverage and lift increases on the down tilting side and decrease on the up tilting side.

The above described principles of my invention and the manner in which they may be embodied in an aeroplane, will be more fully understood from a detail description thereof in connection with the accompanying 115 drawings, in which—

Figure 1 is a top plan view of an aeroplane, embodying certain principles of my invention; Figs. 2 and 3 are respectively front and side elevations; Figs. 4, 5, and 6 are respectively top, front, and side views of a modified form of the aeroplane; Figs. 7, 8, and 9 are respectively top, front, and side views of another modification; Figs. 10, 11, and 12 are views of details to be referred to 120 hereinafter.

Referring to Figs. 1, 2, and 3, it will be seen that the aeroplane shown therein comprises a structure having the general characteristics of a truss extending transversely 125

of the line of flight, with the top and bottom surfaces of the truss utilized as supports for the deflecting areas. The central portion of the truss carries the motive power, load, and steering appliances. In general, this truss comprises a frame composed of thrust members and tension members. The thrust members are preferably of wood and the tension members of steel wire. The joints of the frame and the fastening and tightening means for the tension members are of any known or desired type, and as they constitute no part of my present invention, are not shown in detail in the drawings. The body portion of the device is made up of a light, but relatively strong, frame, comprising horizontal bottom members 1, 2, and corresponding top members 3, 4, spaced apart by the vertical members 5, 6, 7 8. Between the latter members and the comparatively heavy platform 9, particularly adapted to sustain the shock of landing, is located a motor 10. Beneath this platform may be arranged runners, casters, mounted wheels, or other devices adapted to withstand shock and friction of landing. These landing devices may comprise the springs 11, 12, and skids or skees 13, indicated in Fig. 3. The body portion is adequately braced by a system of tension members diagrammatically indicated at 14, 15, Fig. 2, and 16, 17, Fig. 1, but not shown in Fig. 3. The motor is connected to propellers 18, 19, located at the upper corners of said central section. Power is transmitted from the crank shaft of the motor 10 through bevelled gears 20 to vertical shaft 21, thence through bevelled gears 22 to shaft 23. As diagrammatically indicated in Fig. 1, the shaft 23 is connected by bevel gears 23' 24', so as to rotate the propellers 18, 19 in opposite directions. From this central section of the aeroplane, the truss structure extends symmetrically in both directions across the line of flight. Preferably, the entire lower surface of the truss is provided with a cloth or similar covering properly stretched to form lower gliding surfaces 30, 31. The upper sides of the truss are provided with similar surfaces 32, 33, leaving the frame open and unobstructed in the rear of the propellers. The vertical thrust members 34, 34, 34, etc., are preferably stayed against buckling by medial longitudinal thrust members 35.

The above described gliding surfaces 30, 31, 32, 33, constitute the main gliding support for the craft, and one feature of my invention consists in making this part of the structure stable against lateral tilting by causing incipient tilt of the structure to initiate shift of the relations between the center of weight and the leverage and lift of the deflecting surfaces in such manner that the available lifting effect (lift x lever-

age) is increased on the down tilting side or decreased on the up tilting side, or preferably equally and symmetrically increased on the one side and decreased on the other side. The desired change of leverage is brought about by designing the structure in accordance with the principles hereinbefore described, so that a considerable portion of the lifting area is above the horizontal plane passing through the center of gravity G, indicated more particularly at H—H in Fig. 2. As the deflecting areas 32 and 33 are normally at a considerable vertical distance above said horizontal plane, their change of leverage for a given angle of lateral tilt is much greater than for surfaces 30, 31. By referring to the geometrical dotted line diagrams adjacent the surface 33 on Fig. 2, my principle of change of leverage of lifting effect will be at once apparent. Considering, first, a point or small terminal area of the deflecting surface as at a , it will be seen that a lateral tilt about the center of gravity G, sufficient to carry the point a upward to the point b , will have the effect of decreasing its horizontal distance from the vertical line b by an amount equal to the line c , thereby decreasing the leverage of the lift by an amount equal to the distance from the vertical line V, multiplied by the distance c . By reference to the other two dotted line diagrams at the same vertical height from the plane H, it will be seen that if the point a had been located at a^1 , the rotation through the same given angle would have moved the point a^1 to b^1 , or through a horizontal distance c^1 , equal to c . Similarly, if the point a had been at a^2 , the tilting through the given angle would have carried it to b^2 , thereby bringing it nearer V by a distance equal to c^2 , which is the same as c^1 and c . Though the horizontal shift in the direction of the line V is the same in all three cases, it will be noted that the change of leverage measured by the product of this distance of shift multiplied by the distance of the line from V is quite different in the three cases. Taking the distance of shift as unity, the changes of leverage for the three positions, a , a^1 , and a^2 , differ in the proportion of $1 \times 34 = 34$, for point a ; $1 \times 24 = 24$, for point a^1 ; and $1 \times 15 = 15$, for point a^2 . In accordance with the same principles, it will be seen that if the area a had been located with respect to the center of gravity and the horizontal plane thereof in the relation of the point a^3 , the same angle of tilt would have carried the point a^3 to b^3 , and the decrease of horizontal distance from the vertical line V, as indicated at c^3 , would have been about 1.75 times that indicated for points at the lower level a . Considering points a^4 and a^5 , which are at the same vertical distance from H as a^3 , but are hori-

zontally distant from V the same distance as a^1 and a^2 respectively, it will be seen that the horizontal distances moved, as indicated at c^4 and c^5 respectively are the same as at 5 c^3 , but the products representing the change of leverage are less than at a^3 in the same ratio, and for the same reasons that those at a^1 and a^2 are less than those at a . From the various diagrams, it will be seen that 10 a wing of the same structural length as 33, would have greater corrective decrease in leverage if arranged at about 45 degrees from the horizontal and that increase of length of wing set at any upward angle 15 increases the corrective effect for a given tilt. Hence, the stability may be controlled within wide limits. I prefer to make the length of wing such as is necessary to secure the desired supporting area without 20 making the surfaces too wide fore and aft and then to make the heights of the surfaces above the plane of the center of gravity such as will give the desired correcting decrease of leverage on the up tilting side 25 and increase on the down tilting side.

The corrective shift or lift or change of leverage may be effected by arranging the transverse expanse of the deflecting surfaces on upwardly diverging lines, as shown 30 in Fig. 2. When arranged in this manner, the surfaces normally deflect the air downwardly at equal, slightly divergent angles. When so arranged, the planes operate slightly in opposition, and a certain percentage of the power is wasted, because the 35 air is not deflected in exactly vertical parallel planes, but if the divergence is not too great, the loss of energy will not be serious and will be more than compensated for by the simplicity of the construction which is used to support the terminal surfaces in the higher and more efficient position. Moreover, the down tilting areas, as 30, 32, deflect the air at progressively less 40 angles to the vertical, while the corresponding surfaces 31, 33, deflect the air at progressively increasing angles to the vertical, so that when 30 and 32 become approximately horizontal, their dynamic reaction 45 is all lift with no lateral component, while the lateral component of the dynamic reaction on 31 and 32 has been doubled and the vertical component or lift has been correspondingly decreased.

Having described the characteristics of the structure whereby portions of the deflecting area are progressively more effective in 50 changing leverage according to the distance of their terminals above the plane of the center of gravity and their horizontal distance from a vertical line therethrough, and how the vertical component of the dynamic reaction may be made to increase for the down 55 tilting and decrease for the up tilting side, by slanting outwardly and upwardly the di-

rection of the deflecting extremities, it will be evident that where increase or decrease of either or both of these effects is desired, the greatest change may be produced for the least change in area by enlarging or curtailing the deflecting area at the tips of the wings, as indicated by the fore and aft extensions 40, 41.

The above described principle of designing the terminal height of the deflecting surfaces 75 in relation to a horizontal plane through the center of gravity for the purpose of causing the tilting to effect automatic change of the leverage of the dynamic lift, and thereby to correct the tilt, applies equally well to the 80 fore and aft tilt. By reference to the drawings, it will be seen that a relatively small, light truss 42 is rigidly secured to the main truss transversely thereof. It is provided at its ends with small transverse trusses 43, 44, 85 having their tops and bottoms provided with suitable deflecting surfaces 45, 46, 47, and 48. These trusses are pivotally mounted, as at 49, 50, and are provided with crank arms 51, 52, and connecting means 53, whereby decrease of deflecting angle of the forward planes causes increase of the deflecting angles of the rearward planes, and vice versa. Connecting means 53 is operated through bell crank 54, and connection 55, extending 90 within reach of the operator at the motor. The areas 45 and 47 are preferably symmetrical, but one of them may be omitted, if desired. It will be noted that these fore and aft deflecting surfaces are located a suitable 100 distance vertically above the plane H of the center of gravity G. Hence, forward tilt of the structure will operate to increase the leverage of the lift of the forward planes 45, 46, while decreasing that of planes 47, 48. 105 This change of leverage of fore and aft tilt is worked out diagrammatically in Fig. 3 in the same manner that the lateral tilt is worked out in Fig. 2. Thus, movement of the point a of the rear plane by tilting 110 through an angle sufficient to carry it to b, will decrease its horizontal distance from the vertical line V by a distance equal to c, and this change of horizontal distance represented by c multiplied by the total horizontal distance from the line V, will represent the total decrease of leverage. In the case shown, the change represented by c equals 0.7, which multiplied by the distance from V (17.) gives as a product 11.9. The 115 other diagrams on the same horizontal level at different distances from the vertical line V, indicate equal changes of horizontal distance by tilt through the given angle, but the effective leverages for the three positions 120 are proportional to the numbers 17.5, 11.9, and 9.1. The total changes of leverage represented by the same angle of tilt taking effect on planes at a higher level, are indicated on the diagram as being proportional to 17. 130

and 25. It will be noted that the total lift on 45 and 46 may be very small and the total lift on 47 and 48 correspondingly large by reason of adjustment of 53, 54, and 55, but 5 whatever the actual value of the lifts on the forward and aft planes respectively, their leverages will be changed by tilt in the manner and to the extent above described.

As is evident from the drawings, the vertical rudders 60, 61, are located approximately equal distances fore and aft of the main gliding planes. They are pivoted at 62, 63, so as to balance and are provided with pivotally extending bell cranks 64, 65, connected by a member 66, so that when it is desired to change the direction of movement in the horizontal plane, they will deflect the air equally and oppositely, thereby turning the direction of the structure without developing the tendency to lateral tilt which either alone would have by reason of its elevation above the center of gravity.

The propellers are shown forwardly directed so as to pull the craft rather than to 25 push it, and their axes are parallel and disposed at a predetermined angle to the fore and aft extent of the deflecting surfaces, so that in operation the aeroplane will travel in a direction parallel to the axes of the propellers, thereby presenting the deflecting surfaces to the air at a normally definite predetermined angle. As will be seen, the propellers are located substantially at the 30 level of resistance to forward movement and 35 at equal distances on opposite sides of the center of head resistance, so that the center of propulsion and center of resistance is practically coincident and both are above the center of gravity.

40 While I prefer for many purposes the above described structure, wherein change of leverage of lift is combined with change of vertical component of lift, both operating to correct lateral tilt, it is nevertheless possible to utilize the principle of change of 45 leverage in such a degree that stability will be preserved even where the surfaces are arranged so that when the device is on a normal even keel, all deflection of the air 50 is directly downward in vertical, parallel planes. Such an arrangement is shown in Figs. 4, 5, and 6, where the general structure is the same as that previously described, except that the main truss is straight and 55 rectangular, so that the main deflecting areas are approximate planes tilted only in the direction of movement. In this case, the supports 107 and 108 corresponding to 7 and 8 on Fig. 2 are carried a considerable 60 distance below the truss to serve as a suspension frame for the motor 110, stays 111, 112, being extended to the members 105, 106. With this arrangement, the center of 65 gravity may be at G^1 and all of the surfaces being above that level, all of them will op-

erate to change the leverage of the lift upon tilting. The upper surfaces 132, 133, being at a greater distance above the horizontal plane than are the other surfaces 130, 131, will be subject to a greater change of 70 leverage for a given angle of tilt. In this aeroplane, as in that first described, the surfaces at the extremities of the truss will be subject to the greatest change of leverage. In this form of device, any tilt serves 75 to change the direction of deflection of air from the vertical, on all surfaces on both sides of the center, and thereby decreases the vertical component of the total dynamic displacement, instead of causing it to increase on the down tilting side and decrease on the up tilting side, as in the device of Fig. 2. The center of gravity G^1 is so low, however that, for a given angle of the tilt, the aggregate change of leverage on all the 80 deflecting surfaces is much greater than in Fig. 2, and may be made great enough to 85 furnish all the correcting effect required for stability with the advantage that normally all the air is deflected in the most efficient 90 direction. In this device, as in that first described, the propellers are arranged with their axes at a predetermined desired angle with respect to the deflecting surfaces, so that when in motion the sides of the 95 surfaces are directed against the air at a normally constant angle. They are located so that the center of propulsion is approximately coincident with the center of resistance. The skids and other auxiliary devices 100 are also similar to those first described, as will be evident from the drawing. The framing and bracing of the motor platform and its relation to the landing skids is shown more clearly in Fig. 6, where the platform 105 120 is shown in full lines, as is also the enclosing frame, consisting of the upper member 121, vertical members 122, and diagonal tension members 123.

Another expedient whereby weight may 110 be used to insure stability of the aeroplane, involves mounting the weight, which is preferably a necessary part of the apparatus or load, so that it is free to maintain a fixed direction with respect to the pull of 115 gravity even though the deflecting surfaces be tilted through very considerable angles, the resulting relative movement of the parts being utilized to change the area of the deflecting surface or its location or its deflection angle. For such purposes, the gliding part of the structure which carries the deflecting surfaces, may be constructed so that its change of position, due to tilting, causes leverage or lift to change in a direction to correct the tilting, as above described. For purposes of illustration of the invention, however, I have shown the gravity or pendulum member as pivoted to a rectangular gliding structure at a point compara- 120 125 130

tively near the geometrical center of the gliding portion of the structure.

As shown in the drawings, the car or load platform 120 similar to that described with respect to the other figures, is suspended by members 161, 162, extending upwardly to a universal joint on the wing structure. This joint comprises a case 170, mounted in bearings 171, 171, secured to suitable frame work diagrammatically indicated at 172, 172. Suspended from the case 170 are pivots 173, 173, to which are pivoted the car suspending members 161, 162. Referring to Figs. 9, 10 and 11, it will be seen that relative swinging movement in a plane at right angles to the line of flight is permitted by slight rotary movement of the case 170 in bearing 171, while the pivotal connection at 173 permits relative movement in a fore and aft plane. These two pivotal movements and combinations thereof, permit relative swing in any intermediate direction.

As the motor is located in the pendulum portion of the structure, it is necessary for the transmission gear to have the same double pivotal movement on axes coincident with those of the suspension joint just above described. Hence, the vertical shaft 174, geared to the motor at the lower end, is provided with a keyed ball joint 175, permitting relative movement about the same axis as the pivots 173. The female member of this joint drives the shaft 176 carrying beveled gear 177, meshing with beveled gear 178 on propeller shaft 179, which is coaxial with the bearings 171, 171.

From the above described mounting, it results that the motor and load is free to maintain a constant position vertically below the suspension joint, notwithstanding any tilting of the wing structure. By reference to Fig. 8, it will be seen that when the truss tilts laterally, the deflecting area on one side moves nearer to the motor and load, while that on the other side moves farther away. This relative movement is caused to shorten the effective deflecting area on the uptilting side and to lengthen it on the down tilting side. In Fig. 8, the wings are provided with supplemental deflecting area consisting of sliding sections 180, 180, on one side, and 181, 181, on the other side. These are preferably mounted on the tips of the wings, the change of area at this point being more effective. The supplemental sliding sections are preferably mounted so that normally a portion projects beyond the main deflecting area, and the flexible connections diagrammatically indicated at 185, 186, are rigged so as to thrust the sections farther out to secure a greater lift on the down tilting side and to draw in those on the other side, to secure a decreased leverage and lift. It will be obvious that many other connections may be devised changing the

lift or its leverage, in accordance with the relative shift of the gliding structure and the pendulous portion.

If desired, the supplemental sections or ailerons, may be mounted pivotally after the manner indicated in Fig. 12, instead of slidably, as shown in Fig. 8. In said Fig. 12, the supplemental surface 280 is shown as pivoted at 200 to the extremity of a main deflecting surface. In this case, the relative movement of wing tips with respect to the pendulum portion may be applied directly to the supplemental plane by means of links 201. In the operation of this arrangement, the supplemental surface 280 may be normally inclined laterally so that the deflection has a considerable lateral component and the upward resultant or lift is considerably less than the total dynamic reaction. With such a device, downward movement of a wing tip will have the effect of causing outward movement of links 201, thereby swinging the supplemental surface 280 to a position where the deflection is more directly downward and lifting effect is thereby increased. In case of reverse movement, the links 201 cause the surfaces 280 to swing downwardly about the pivot 200; so that the deflection of air becomes progressively more lateral and has less and less vertical component or lift. In each case the leverage of the lift also changes.

It will be noted with respect to forward and aft tilt, that the supplemental surfaces 145, 146, 147, 148, have an initial position at a considerable distance vertically above the horizontal plane passing through the center of gravity, and hence have a certain amount of automatic correcting action by reason of the change of the leverage which results from fore and aft tilt. The amount of the lift on the forward planes 145, 146, may be increased and that on the rear planes 147, 148, decreased automatically by the relative movement with respect to the pendulum, if desired. For this purpose, it is only necessary to connect the bell crank 190, controlling the deflecting angles on said planes by a link 191 to some part of the pendulum which will give a required leverage and relative movement. As shown in the drawings, link 191 is connected to the short arm 192 of a pivotal lever, the long arm 193 of which may be adjustably fixed with respect to the pendulum by means of the sector 194, the handle 195 for effecting such adjustment being within reach of the operator.

It will be evident that any one or all of the above described principles of utilizing weight for the purpose of causing tilt to be automatically self correcting in an airplane, may be utilized separately or together in any desired combination to produce any required degree of stability or automatic self righting quality.

While I have herein fully shown and described, and have pointed out in the appended claims certain novel features of construction, arrangement, and operation which characterize my invention, it will be understood by those skilled in the art that various omissions, substitutions, and changes in the forms, proportions, sizes, and details of the device and of its operation, may be made 10 without departing from the spirit of my invention.

I claim:

1. An aeroplane comprising a lifting area and weights supported thereby, said aeroplane being arranged with its centers of resistance and of propulsion a considerable distance above the center of gravity and having its lifting area per unit length greater toward the extremities than at the center, 20 in such degree as to render the aeroplane self-correcting as against inequalities of effort found in atmospheric air, up to a desired percentage of the total lift of the aeroplane.
- 25 2. A flying machine comprising a gliding structure provided with a supporting surface having reefing extremities, in combination with a pendulous weight and means

whereby tilt of the gliding structure with respect to the weight operates to extend or 30 reef said extremities so as to correct the tilt.

3. A flying machine comprising a gliding structure provided with a supporting surface having reefing extremities, in combination with a weight mounted for relative 35 movement by gravity upon tilt of the gliding structure, and means whereby said relative movement operates to extend and reef said extremities so as to correct the tilt.

4. An aeroplane comprising a sustaining 40 plane frame, a longitudinal driving shaft, a pendant frame pivotally mounted on an axis coincident with the shaft axis, a motor in said pendant frame, transmission gearing between said motor and shaft, ailerons 45 mounted on the plane frame and connections whereby the ailerons are operated by a movement of the pendant frame and plane frame with respect to each other.

Signed at New York city, in the county 50 of New York and State of New York this 25th day of August, A. D. 1908.

PETER COOPER HEWITT.
